UNITED STATES PATENT OFFICE.

CHRISTIAN F. WILSON, OF FARGO, NORTH DAKOTA.

TOY ACROBAT.

Application filed April 11, 1923. Serial No. 631,388.

To all whom it may concern:

Be it known that I, CHRISTIAN F. WILSON, a citizen of Denmark, residing at Fargo, in the county of Cass and State of North Dakota, have invented certain new and useful Improvements in Toy Acrobats, of which the following is a specification.

5 My invention relates to a toy representing an acrobat turning somersaults and performing sundry other acrobatic stunts on a cord suspended between two parallel bars.

10 The main object of the invention is to provide a toy of this character that is so constructed that the acrobat or manikin will always swing free of the side bars even if not held in vertical position, and that the limbs will always turn freely, so as not to catch in each other or in the trunk of the manikin.

15 In the accompanying drawing one embodiment of the invention is illustrated, and;

Figure 1 is a front elevation of the toy with the manikin suspended freely therein;

20 Figure 2 is a longitudinal section along line 2—2 of Figure 1;

Figure 3 is a partial front elevation showing the upper part of Figure 1 in larger scale and with the manikin supposed to be swung upwardly; and

25 Figure 4 is a partial vertical section along line 3—3 of Figure 2 with the trunk in inverted position corresponding to the arrangement shown in Figure 3.

30 The toy consists of two parallel bars 10 of rectangular cross section and connected by a fulcrum block 11 at about one fourth of the length of the bars from the lower end thereof. The bars and the block are held together by means of screws or pins 12 placed in the center of the block, and the ends of the latter are preferably slightly rounded or beveled as at 13 to permit a slight roll of the bars thereon, as indicated

35 in Figure 1.

The lower extension 14 of the bars 10 form handles of a suitable length to be carried in a person's hand. The extreme upper end of the bars are perforated as at 15 and 16 to form a pair of apertures situated one above the other in longitudinal direction of each bar. Through these apertures is threaded a piece of string or catgut, which is tied together as at 18 on the outer side of one of the bars 10, as seen in Figure 3, and on the part of the string 17 running

through the upper apertures 16 are formed spaced knots constituting stops 19 at the same distance inwardly from the respective bars 10.

60 The acrobat or manikin consists of a trunk or body portion 20 having a head 21 formed integrally therewith or rigidly secured thereon. This trunk 20 is of uniform thickness from the top to near its bottom where, however, it is tapered as best seen at 22 for a reason that will be explained later. At the portion of the trunk representing the shoulders the upper limbs or arms 23 are journaled on a short piece of string or wire 24 knotted on the outside of the arms 23, as seen at 25, so as to permit free turning of the arms at the shoulders. The portion of the arms representing hands 26 are pierced in two places as at 27 and 28 to form apertures for the operating string 17. These apertures are preferably spaced apart the same distance as the apertures 15 and 16 in the side bars 10 and are situated one above the other in the longitudinal direction of the arms 23. In assembling the arms between the bars, the toy is held inverted and the string threaded through the inner aperture 15 in one of the bars, then through the apertures 28 of both arms to the aperture 15 in the opposite bar, thence through aperture 16 and apertures 27 in the arms and lastly through aperture 16 in the other bar and knotted on the outside thereof as at 18. In this manner, the operating string 90 or cord 17 forms a rectangular loop, which when stretched permits outward displacement of the upper ends of the bars 10, so that the distance between them at this place is greater than at the handles 14. When 95 assembling the arms on a string in this manner, care has to be taken that the knots or stops 19 are situated between the arms, as seen in Figure 3, near the outer apertures 27.

100 At the lower end of the trunk the limbs forming the legs 29 are secured in the same manner as the arms 23, that is to say, by means of a short piece of string or wire 32 knotted at both sides as at 30 to hold the legs loosely to the body, so that they can turn around the wire. The inner side of the legs at the joint are tapered as at 31 in the opposite direction to the taper 22 on the trunk. In this manner the legs 29 will hang parallel, when the toy is held in upright position with the acrobat or manikin hanging down loosely, while when the trunk is in-

verted as in Figure 4, the feet 33 of the acrobat will spread apart, so that they will straddle the shoulders of the manikin and not catch in the knots 25 at this place, as indicated in Figure 4 and in dotted lines in Figure 1. For the same reason the inner side of the arms 23 are tapered so that when the manikin is suspended and hanging downwards between the bars, as in Figure 1, 10 the distance between the hands 26 will be greater than the distance at the shoulders of the manikin.

The length of the operating string 17 is such that it will permit the manikin to 15 swing down into the position shown in Figure 1 to be suspended from the string when the bars 10 are parallel and no pressure exerted on the handles 14, in which case the operating string 17 is twisted one half turn, 20 as seen in Figure 1. When now a pressure is given by the hand on the two handles 14, the bars 10 will roll slightly on the ends 13 of the block 11 around their fulcrum points formed by the screws or pins 12, so that the 25 upper ends of the bars will spread apart. In doing this the operating string 17 is tensioned and the twist therein stretched out, so that the arms 23 will be swung upwards, as indicated in Figure 3, bringing the trunk 30 of the acrobat with it. If a quick pressure is exerted on the handles 14, the manikin will swing upwardly in extended position, but if a slow pressure is exerted, the trunk will turn at the shoulders and the legs 29 35 around their journal point on the string 32.

The fact that the legs and trunk 20 are tapered at the joint on the string 32 will compel the feet 33 to spread apart without catching anywhere on the trunk or arms of the manikin. On account of the knots 19 40 being symmetrically positioned between the bars 10, the manikin will be compelled to swing centrally between the bars and for that reason neither the legs 29 nor the trunk 20 of the manikin can catch in the bars 10. 45

Having thus described the invention what is claimed as new is:

A toy comprising spaced side bars, a fulcrum block fitting between and secured to the side bars in spaced relation to the lower ends thereof, the upper ends of the side bars being provided with spaced apertures, a manikin suspended between the side bars and including a torso having leg and arm members pivotally connected therewith, the arm members having their outer ends normally diverging and provided with upper and lower apertures, and an endless flexible element threaded through the apertures in the side bars and arm members, said flexible element being knotted to form spaced stops disposed between the diverging ends of the arms and bearing against the inner faces thereof at the adjacent apertures therein for centering said arms on the flexible element and holding the outer ends of said arms normally in diverging relation. 55

In testimony whereof I affix my signature.

CHRISTIAN F. WILSON. [L. S.]
